UNITED STATES PATENT OFFICE

JAMES N. HOUSE, OF JACKSON, MICHIGAN, ASSIGNOR TO THE SPARKS-WITHINGTON COMPANY, OF JACKSON, MICHIGAN, A CORPORATION OF OHIO

DESIGN FOR A RADIOCABINET

Application filed July 30, 1929. Serial No. 32,247. Term of patent 7 years.

To all whom it may concern:

Be it known that I, JAMES N. HOUSE, a citizen of the United States, residing in the city and county of Jackson, Michigan, have invented a new, original and ornamental Design for Radiocabinet, of which the following is a specification reference being had to the

accompanying drawing, forming part thereof.

The figure is a perspective view of the radio cabinet.

I claim:

The ornamental design for a radiocabinet substantially as shown.

JAMES N. HOUSE.
